UNITED STATES PATENT OFFICE.

JOSEPH SIGL, OF SEYMOUR, WISCONSIN.

PUMP CLEVIS.

Application filed May 14, 1923. Serial No. 638,906.

This invention relates to a pump attachment and more particularly to a pump clevis adapted to be quickly attached to and detached from the spout of the pump.

5 One of the objects of the invention is to provide an improved pump clevis which can be adjusted to fit pump spouts of various sizes.

10 A further object of the invention is to provide a flexible construction by means of which the base or cup of the clevis is permitted to properly seat itself on the mouth of the spout of the pump regardless of the angular position of the mouth with respect 15 to the spout.

A still further object of the invention is to utilize the means for adjusting the cup to fit pump spouts of various sizes and to also retain a plurality of washers in the cup.

20 Another object of the invention is to provide a novel form of clamping means which can be quickly and easily detached from the cup.

25 These and other objects are obtained by providing a construction and arrangement of the various parts in the manner herein-after described and particularly pointed out in the appended claims.

30 Referring to the drawings, Fig. 1 is a perspective view of a pump having my improved pump clevis mounted thereon.

Fig. 2 is a front elevational view of my improved pump clevis showing the manner in which the clamping member is pivoted 35 to the cup.

Fig. 3 is a top plan view showing the manner in which the set screws may be adjusted to accommodate different sizes of pump spouts.

40 Fig. 4 is a front elevational view, partly in section, of the cup, showing the manner in which the washers are positioned and retained in the cup.

Fig. 5 is a side elevational view of the 45 pump spout showing the lug thereon to which the clamping member of the clevis may be detachably secured, and

50 Fig. 6 is a detailed side elevational view showing the manner in which the clamping member is detachably secured to the cup.

For the purpose of illustration I have shown my invention mounted on a pump 10, which comprises the usual pump stand or base 11 having an outwardly and downwardly curved spout 12. The spout 12 is provided with an upwardly projecting lug 13

and a mouth 14. Positioned on the rear side of the pump 10 opposite the spout 12 is a removable cap 15 which may be substituted for a supplemental conduit or spout when 60 it is desired to prevent the flow of water through the primary spout 12. The pump is provided with the usual hand operating lever 16 pivoted to the arm 17 for reciprocating the piston 18 for pumping the water. 65 The pump mechanism just described does not form any part of the present invention.

In connection with my improved pump clevis, I have provided a novel construction which can be quickly adapted to fit 70

pumps of various sizes and at the same time can be adjusted to properly seat the cup on the mouth of the spout in such a manner that leakage between the cup and the spout is entirely eliminated. This construction 75

comprises a cup 19 having a peripherally arranged band 20 and a seat 21 so as to form a socket 22 adapted to receive the mouth 14 of the spout 12. Extending downwardly from the seat portion 21 of the 80 cup and formed integrally therewith is a reduced hose connection nozzle 23. The nozzle 23 has a vertically extending bore which communicates with the socket 22 of the cup 19. The lower end of the nozzle 85

23 is provided with two spaced peripherally arranged grooves 25, the edges of which are adapted to frictionally engage a hose which may be attached to this nozzle. In order to 90

centrally maintain the socket 22 of the cup 19 on spouts of various sizes, I have provided three set screws 26 threaded into the band 20 of the cup 19 and arranged or spaced apart at substantially 120 degrees about the cup as clearly shown in Fig. 3. These set 95

screws are locked in their adjusted position by means of lock nuts 27. The set screws are also employed to retain a plurality of washers 28 and 29 on the seat 21 of the cup by having the inner ends of the 100

set screws 26 extending over the washers and retain them between the screws and the seat of the cup. The washer 28 is perforated at 30, while the washer 29 is imperforated as shown in Fig. 4. When it is de- 105

sired to entirely shut off the flow of water from the spout 12 the imperforated washer 29 is positioned in the socket 22 on top of the perforated washer 28 and the cup 19 is clamped in position on the spout 12 with the mouth 14 securely seated on the imperforated washer 29, thus entirely closing 110

or shutting off the flow of water through the spout 12. When the flow of water through the spout 12 is shut off the water is usually directed through a supplemental 5 conduit or spout substituted in the place of the cap 15 on the rear side of the pump. If it is desired to permit the flow of water through the spout 12 the imperforated washer 29 is removed and the perforated washer 10 28 is clamped between the mouth 14 of the spout and the seat 21 of the cup forming a water tight connection between these members. In order to properly seat the cup on the mouth of the spout, I have provided 15 a novel construction, which comprises two oppositely disposed pins 31 formed integral- 20 ly with and positioned on the outer sides of the band 20 of the cap 19. Extending downwardly from each of these pins is a 25 projection 32. Pivotsly connected to the pins 31 in a manner to be easily detached therefrom is a U-shaped member 33. The U-shaped clamping member is provided 30 with apertures in both legs thereof. Com- 35 municating with each of these apertures 34 and extending upwardly with respect thereto is a narrow slot 35, which is adapted to permit the U-shaped clamping member to be quickly detached from the pins 31 and 30 projections 32 on the cup 19 when the clamping member is swung downwardly with respect to the cup to a position substantially 180 degrees from the position shown in Fig. 2. The upper central portion 35 of the U-shaped member 33 is provided with a threaded aperture 36 which is adapted to receive in threaded engagement therewith a clamping bolt 37. The upper end of 40 the clamping bolt 37 is provided with wings 38 for manually adjusting the bolt with respect to the U-shaped member when clamp- ing my improved clevis to a pump spout. The lower end of the bolt 37 has swivelling-

ly secured thereto a curved bracket 39 which is adapted to engage the lug 13 on the pump 45 spout 12 when the clevis is properly seated on the spout.

By reason of the pivotal connection of the U-shaped member 33 with the cup 19, it will be seen that a proper seating of the mouth 50 14 of the spout 12 on the washers in the cup 19 will readily be had when the clamping bolt 37 is adjusted to a position in which the curved swivelling bracket 39 engages the lug 13 on the spout 12. From the construction 55 just described, it will be seen that a very efficient and practical pump clevis has been provided and one which is adapted to fit pumps of various sizes in such a manner as to prevent any possibility of leakage of 60 water between the cup and the spout.

While in the above specification, I have described one embodiment which my invention may assume in practice, it will be understood that modifications may be made 65 without departing from the spirit and scope of my invention.

What I claim as my invention and desire to secure by Letters Patent is:

A pump clevis comprising a cup, a hose 70 connection extending downwardly from said cup, a plurality of pins extending outwardly from said cup, a clamping member having oppositely disposed apertures adapted to pivotally receive said pins, there being slots in said clamping member communicating with the apertures therein, and means carried by said pins co-operating with the slots in said clamping member for detachably connecting the clamping mem- 75 ber to said cup. 80

In testimony whereof I have signed my name to this specification, this 20th day of April A. D. 1923.

JOSEPH SIGL.
